UNITED STATES PATENT OFFICE

2,599,388

SHAPING MACHINE MECHANISM

Harold E. Hicks, Webster Groves, Mo., assignor
to Gemco Shaper Company, a corporation of
Missouri

Application May 23, 1947, Serial No. 749,994

15 Claims. (Cl. 90—38)

1

The present invention relates generally to shaping machines, and the like, and more particularly to a consolidated shaping machine mechanism controlling manual and power traversing of the work table and manual and power vertical movement of the cross rail.

An object of the present invention is to provide a novel adjustment and action setting mechanism for a shaping machine for selective vertical movement of the cross rail and traversing movement of the work table.

Another object is to provide a novel consolidated shaping machine mechanism which incorporates a single actuating hand wheel, or the like, in one position thereof through which gearing is set for manual or power horizontal movement of the work table and in another position thereof gearing is set for manual or power vertical movement of the cross rail which supports and carries the work table.

Another object is to provide a novel consolidated shaping machine mechanism for selectively effecting horizontal traversing movement of the work table and vertical movement of the cross rail which incorporates a dial construction with two graduated scales calibrated for horizontal and vertical movements, respectively, which alternately automatically line up with a single index mark to provide readings for the particular movement for which the mechanism is set.

Another object is to provide a consolidated shaping machine mechanism for selectively setting the machine for horizontal traversing movement of the work table and vertical movement of the cross rail through a single hand wheel, or the like, which is simple and rugged in construction, thereby insuring low maintenance requirements and long service with minimum shutdown due to mechanical trouble.

Another object is to provide a novel adjustment and setting mechanism for shaping machines, and the like, which incorporates a single member for selectively setting the mechanism to effect horizontal traversing movement of the work table or vertical movement of the cross rail, and which, in either selected set position, may be employed to horizontally adjust the work table and vertically adjust the cross rail, respectively.

Another object is to provide a novel consolidated shaping machine work table and cross rail setting and adjustment mechanism which may be readily employed by an operator with maximum efficiency even after very little instruction, and which simplifies the setting and adjustment operations to which it appertains.

2

The foregoing and other objects and advantages are apparent from the following description taken with the accompanying drawings, in which:

5 Fig. 1 is a side elevational view of a shaping machine incorporating the present novel setting and adjustment mechanism;

Fig. 2 is an end elevational view thereof looking towards the work table end;

10 Fig. 3 is a fragmentary end elevational view similar to Fig. 2, but with the work table removed to illustrate more clearly the cross rail;

Fig. 4 is an enlarged fragmentary cross-sectional view substantially on the line 4—4 of

15 Fig. 1;

Fig. 5 is a still further enlarged cross-sectional view on the line 5—5 of Fig. 4;

Fig. 6 is an enlarged longitudinal central cross-sectional view on the line 6—6 of Fig. 5
20 through the clutch and associated constructions;

Fig. 7 is a cross-sectional view on substantially the line 7—7 of Fig. 4;

Fig. 8 is a diagrammatic view of the present
25 novel adjustment and selective setting mecha-

nism; and

Fig. 9 is an enlarged view of the end of the
main feed shaft looking at the rapid traverse
sprocket and pawl.

Referring to the drawings more particularly by reference numerals, 10 indicates generally a
30 shaping machine incorporating the present invention (Figs. 1 and 2), and 12 indicates generally a consolidated movement setting and adjustment mechanism constructed in accordance with the teachings of the present invention, Fig. 8 showing diagrammatically the layout thereof in association with the power mechanism 13 of the machine 10.

The shaping machine 10 shown in the drawings (Figs. 1 through 3) is of known construction except for the mechanism 12, and includes a base 14 and a column or casing 15. Slidably mounted on the column 15 is a ram 16 which supports through the usual head 17 a selected removable cutting tool 18.

40 At its front end, the casing 15 is formed with spaced vertical guide members 20 which receive complementary channels (not shown) of a cross rail 21. A work table 22 is supported on the cross rail 21 for horizontal traversing movement.

A motor 25 controlled by "on" and "off" buttons 23 and 24, respectively, is mounted on the base 14 (Figs. 1 and 8) and is connected to the ram 16 for reciprocation thereof, the connecting means including a belt 26, a clutch 27, a selective speed transmission 28, bull gears 29

and 30 selectively actuated by the speed transmission 28 through gears 31 and 32, respectively, mounted on a shaft 33, a crank pin 34 secured to the bull gear 29 having a crank block (not shown) mounted thereon, a rocker arm 37 (Fig. 1) mounted on a supported stub shaft 38 and having the usual slide surfaces receiving the just mentioned crank block to effect reciprocation of the rocker arm 37, and a link 39 pivotally connected to the free end of the rocker arm 37 by a pivot post 40 at one end and pivotally connected to the ram 16 by a pivot post 41. Hence, rotary movement of the rotor of the motor 25 is translated into reciprocating movement of the ram 16.

The bull gears 29 and 30 are mounted on one end of a shaft 45, the other end of which supports a cam 46 which engages a cam follower 47 suitably mounted in the casing 15 for oscillative movement. The cam follower 47 is formed to include a gear sector 48 which meshes with a gear sector 49 formed as part of a pawl supporting member 50 which is freely mounted on a main feed shaft 51 rotatively supported by the casing 15. A pawl 52 is pivotally supported on the member 50 on a headed post 53 in position for engaging the teeth of a ratchet 55 keyed to the shaft 51. A cam 56 supported by an annular member 57 freely mounted on the hub of the ratchet 55 determines the extent of rotary movement imparted to the ratchet 55 by the pawl 52. The cam 56 may be positioned so that the pawl 52 rides over its periphery for a part of its movement, thereby being kept out of engagement with the teeth of the ratchet 55 for this portion of its movement. Adjusting means for the cam 56 is provided in the form of a lever 60 mounted for rotary movement on the stub shaft 61 supported by the wall of the casing 15, a link 62 being connected at one end to an arm 63 secured to the stub shaft 61 for rotary movement therewith and at its other end to an arm (not shown) connected to the cam supporting member 57. Hence, rotation of the lever 60 is imparted to the member 57 and its supported cam 56, thereby providing for adjustment of the cam 56 to determine the amount of feed imparted to the ratchet 55 at each stroke of the ram 16.

A beveled gear 65 is mounted on the shaft 51 adjacent the ratchet 55, being secured to the shaft 51 for rotation therewith by a spring loaded safety cone clutch 66. Meshing with the beveled gear 65 is a beveled gear 67 secured as by a key to one end of a shaft 68. A miter gear 69 having an elongated hub 70 is connected to the other end of the shaft 68 by a long keyway 71 in the shaft 68 and a key 72. Telescopic movement between the shaft 68 and the hub 70 is thus provided to permit vertical movement of the cross rail 21.

The selective movement setting and adjustment mechanism 12 includes the aforesaid miter gear 69 and miter gears 73 and 74, which mesh with the miter gear 69 and which are freely rotatable on a shaft 76. A clutch 75 (Figs. 4 through 6 and 8) is keyed to the shaft 76 between the gears 73 and 74 by a key 77 secured to the clutch 75 by a setscrew 78 and slidably in a keyway 79 formed in the shaft 76. The clutch 75 includes opposed sets of teeth 80 and 81 which are selectively engageable with the teeth of the miter gears 73 and 74, respectively. A shifter device 82 is provided for shifting the clutch 75 which includes a rotatably mounted cam 83 adapted to move the clutch 75 selectively into

engagement with the gears 73 and 74 through contact with the walls of an annular channel 84 formed in the clutch 75. The keyway 79 is longer than the shifting requirements of the clutch 75 in order to provide for longitudinal shifting of the shaft 76 independently of movement of the clutch 75, as is more particularly described below.

The shaft 76 is supported, in the main, within 10 a housing 85 secured to one end of the cross rail 21 by a suitable split ring 86 and screws 87, the shaft 76 being rotatable in a bearing 88 supported at the inner end of the housing 85 and a member 89 supported at the outer end thereof. 15 A hand wheel 90 is secured to the free end of the shaft 76 for both rotation and longitudinal movement therewith. A hub 91 is secured to the hand wheel 90 for rotation therewith and receives annular dials 92 and 93 which are frictionally mounted 20 on the hub 91 for independent annular adjustment. The dial 92 includes graduations (Fig. 4) calibrated for vertical movement of the cross rail 21, and the dial 93 includes graduations calibrated for horizontal movement of the work table 25 22. The dials 92 and 93 are selectively disposed for reading in conjunction with a pointer 94 on the member 89. A spring loaded ball detent 95, mounted in a well provided in the member 89, cooperates with spaced annular grooves 96 and 30 97 formed in the shaft 76 to maintain the shaft 76 in selected driving position, as is more particularly pointed out below. Fig. 4 shows the shaft 76 in neutral position.

Near the inner end of the shaft 76 is secured 35 a gear 100 for rotation therewith (Fig. 4). The gear 100 is adapted to mesh with a gear 101 spaced longitudinally therefrom and mounted on the free end of a cross feed threaded screw shaft 102 mounted in bearings 103 supported in the 40 walls of the cross rail 21. The screw shaft 102 receives a rider nut 104 which is secured to the work table 22 by suitable bolts 105 (Fig. 8).

The gear 100 also is adapted to mesh with a gear 108 secured to the end of the shaft 109 mounted at one end in a bearing 110 and at the other end in a bearing sleeve 111. The shaft 109 has a worm 112 formed integral with the end thereof remote from the gear 108. The worm 112 meshes with a worm gear 113 (Fig. 8) which threadedly engages an elevating screw shaft 114 (Fig. 3). The worm gear 113 is mounted in a suitable bearing secured to the cross rail 21 so that rotation of the worm gear 113 effects vertical movement of the cross rail 21.

There is provided mechanism for rapidly traversing the cross rail 21 when such movement is desired, which includes for power a motor 120 mounted on the side of the casing 15 and set in motion through a lever 119 (Figs. 1 and 8).

60 The rotor shaft 121 of the motor 120 has secured to the end thereof for rotation therewith a small gear 122 which meshes with a larger gear 123 secured to a shaft 124 suitably mounted in the casing 15. Also secured to the shaft 124 for 65 rotation therewith is a sprocket 125 around which is trained one end of a continuous chain 126, the other end thereof being trained around a larger sprocket 127 freely rotatable on the shaft 51. Pivotally connected to one face of the 70 sprocket 127 is a pawl 128 (Figs. 8 and 9) which is urged by a spring 129 mounted in a retainer 130 into engagement with the teeth of a ratchet 132 secured to the free end of the shaft 51 by a suitable pin 133. As is manifest, the just described construction prevents the regular feed

5

movement of the shaft 51 from driving the motor 120, but the motor 120 is effective therethrough to rapidly rotate the shaft 51 regardless of feeding action from the motor 25, since the pawl 128 in its relation with the ratchet 132 will effect overrunning of the shaft 51 in the normal direction of feed.

Operation

The presently provided selective movement setting and adjustment mechanism 12 is effective, as is clear from the foregoing, through the manipulation of the single hand wheel 90. In Fig. 8, the shaft 76, which is longitudinally movable by the manipulation of the hand wheel 90, is shown in neutral position, the gear 100 secured to the end thereof being disposed between the gears 101 and 108. The clutch 75 is also shown in neutral position.

When it is desired to manually adjust the position of the work table 22 horizontally, pressure is applied on the hand wheel 90 to move the shaft 76 inwardly to bring the gear 100 into meshing engagement with the gear 101. At the same time, the dial 93 is brought into position to register with the pointer 94 on the member 89. Rotation of the hand wheel 90 will then effect horizontal traversing movement of the work table 22 which will be indicated on the dial 93. If a zeroing action is being effected, the dial 93 may be rotated manually against its frictional engagement with the hub of the hand wheel 90 to set it to zero position. It is to be noted that the spring loaded detent 95 engages the groove 97 in the shaft 76 to maintain the shaft 76 in selected position and the gear 100 in engaging relation with the gear 101.

Should it then be desired to manually adjust the position of the cross rail 21, outward pulling force is applied to the hand wheel 90 to overcome the spring loaded detent 95, after which the shaft 76 is pulled outwardly until the gear 100 is in meshing engagement with the gear 108. In this relationship, the spring loaded detent 95 will be in engagement with the groove 96. The dial 92 will be in registry with the pointer 94. Rotation of the hand wheel 90 will then effect vertical movement of the cross rail 21, up or down, depending upon the rotation of the hand wheel 90. As in the case of the dial 93, the dial 92 may be annularly rotated against its frictional engagement with the hub of the hand wheel 90 for zeroing action.

For power traversing of the work table 22, the gear 100 is moved into engagement with the gear 101 by pressure applied to the hand wheel 90, as in the case of manual adjustment. The clutch 75 is then moved into engagement with either gear 73 or gear 74 through manipulation of the shifter device 82. Thereafterwards, when power is applied to the shaping machine 10 from the motor 25, the table 22 will be moved an increment following each stroke of the ram 16 when the ram 16 is set for reciprocation, or it will move independently if the ram 16 is not connected for movement. The work table 22 is returned to its initial cutting position by throwing the clutch 75 into engagement with the other gear 73 or 74, which reverses the rotation of the shaft 76. Rapid return traversing movement is effected by employing the motor 120 and the mechanism driven thereby which functions as set forth above.

Power raising and lowering of the cross rail 21 may be effected through engaging the gear 100 with the gear 108 through the medium of the

6

hand wheel 90, engaging the clutch 75 with the gear 73 or 74, depending upon direction of movement desired, and energizing the motor 25.

It is to be observed that the dials 92 and 93 are automatically moved into registry position with the pointer 94 on the member 89 as the gear 100 is moved into engagement with the gears 108 and 101, respectively. As is stated above, the dials 92 and 93 are calibrated to indicate the amount of vertical movement of the cross rail 21 and the traversing movement of the work table 22, respectively.

It is apparent there has been provided a selective movement setting and adjustment mechanism for shaping machines, and the like, which fulfills the objects and advantages sought therefor.

It is to be understood that the foregoing description and the accompanying drawings have been given by way of illustration and example. It is also to be understood that changes in form of the several parts, substitution of equivalent elements, and rearrangement of parts, which will be readily apparent to one skilled in the art, are contemplated as within the scope of the present invention, which is limited only by the claims which follow.

What is claimed is:

1. In a machine of the kind described including a transversely movable work table, a vertically movable work table support, and power means, in combination, mechanism for selectively connecting the power means with the work table for power traversing the same and with the work table support for power raising or lowering the same including a single movable power transmitting member alternately operatively connectible between the power means and the work table or work table support.
2. In a machine of the kind described including a transversely movable work table, a vertically movable work table support, and power means, in combination, mechanism for selectively connecting the power means with the work table for power traversing the same and with the work table support for power raising or lowering the same including a single rotatable and axially movable member manually axially movable and selectively manually or power rotated.
3. In a machine of the kind described including a transversely movable work table, a vertically movable work table support, and power means, in combination, mechanism for selectively connecting the power means with the work table for power traversing the same and with the work table support for power raising or lowering the same including a rotatable and axially movable member manually axially movable and selectively manually or power rotated, a pair of dials axially movable with said member, one dial being calibrated to read traversing movement of said work table and the other vertical movement of said support, and a single stationary pointer, said dials being movable into registry with said pointer to correspond to the power connection of the work table and support, respectively.
4. In a machine of the kind described including a transversely movable work table, a vertically movable work table support, and power means, in combination, mechanism for selectively connecting the power means with the work table for power traversing the same and with the work table support for power raising or lowering the same including a single movable power transmitting member alternately operatively connectible between the power means and the work table or work table support.

nectible between the power means and the work table or work table support, and manually operable means bodily movable for moving said power transmitting member into said selective connecting relation, said manually operable means being manually rotatable to adjust the selected connected work table or support independently of said power means.

5. In a machine of the kind described, in combination, a work table support, means mounting said work table support for vertical movement including means actuatable for imparting vertical movement to said support, a work table supported by said support for traversing movement to said table, a rotatable and longitudinally reciprocable member, means connected to said member adapted for selective engagement with said support actuatable means and said table actuatable means, means for moving said member selectively longitudinally to engage said means connected thereto with said support actuatable means or said table actuatable means, means for rotating said member to effect movement of the selected actuatable means, said means including a single member mounted for rotational and reciprocal movements adapted to receive and transmit push and pull forces and rotational forces.

6. In a machine of the kind described, in combination, a work table support, means mounting said work table support for vertical movement including means actuatable for imparting vertical movement to said support, a work table supported by said support for traversing movement, means actuatable for imparting traversing movement to said table, a rotatable and longitudinally reciprocable member, means connected to said member adapted for selective engagement with said support actuatable means and said table actuatable means, means for moving said member selectively longitudinally to engage said means connected thereto with said support actuatable means or said table actuatable means, and means for rotating said member to effect movement of the selected actuatable means, a pair of annular dials connected to said member for rotation and longitudinal movement therewith, and a single stationary index, one dial being calibrated to indicate traversing movement of said table and the other vertical movement of said support, said dials being disposed to register with said index in accordance with the selected respective actuatable means.

7. In a machine of the kind described, in combination, a work table support, means mounting said work table support for vertical movement including means actuatable for imparting vertical movement to said support, a work table supported by said support for traversing movement, means actuatable for imparting traversing movement to said table, power means including energization means, and mechanism including a force transmitting member for connecting said two actuatable means selectively with said power means, said mechanism also including means for manually applying a force to said force transmitting member independently of said power means for selective manual adjustment of said support and said work table.

8. In a machine of the kind described, in combination, a work table support, means mounting said work table support for vertical movement including means actuatable for imparting vertical movement to said support, a work table supported by said support for traversing movement, means actuatable for imparting traversing movement to

said table, power means including energization means, and mechanism including a bodily movable and rotatable force transmitting member for connecting said two actuatable means selectively with said power means, said mechanism also including a member for manually both bodily moving said force transmitting member and applying a rotational force to said force transmitting member independently of said power means for selective manual adjustment of said support and said work table.

9. In a machine of the kind described, in combination, a work table support, means mounting said work table support for vertical movement including means actuatable for imparting vertical movement to said support, a work table supported by said support for traversing movement, means actuatable for imparting traversing movement to said table, power means, a longitudinally movable and rotatable shaft having a gear secured to one end, a hand wheel secured to said shaft, said hand wheel being adapted to receive manual push-pull and rotational forces, said gear being selectively connectible through longitudinal movement of said shaft with said two actuatable means, and clutch means connecting said power means with said shaft for selective forward and reverse drive, said shaft being selectively manually rotated through said hand wheel and power rotated through said power means in any longitudinal position thereof.

10. In a machine of the kind described, in combination, a work table support, means mounting said work table support for vertical movement including means actuatable for imparting vertical movement to said support, a work table supported by said support for traversing movement, means actuatable for imparting traversing movement to said table, power means, a longitudinally movable and rotatable shaft having a gear secured to one end, a hand wheel secured to said shaft, said hand wheel being adapted to receive manual push-pull and rotational forces, said gear being selectively connectible through longitudinal movement of said shaft with said two actuatable means, clutch means connecting said power means with said shaft for selective forward and reverse drive, said shaft being selectively manually rotated through said hand wheel and power rotated through said power means in any longitudinal position thereof, a pair of dials supported on said shaft adjacent said hand wheel, and a single stationary pointer, one of said dials being calibrated to read traversing movement of said work table and the other to read vertical movement of said support, said dials being movable with the shaft and being adapted to selectively register with said pointer in accordance with the selected actuatable means.

11. In a machine of the kind described, in combination, a work table support, means mounting said work table support for vertical movement including means actuatable for imparting vertical movement to said support, a work table supported by said support for traversing movement, means actuatable for imparting traversing movement to said table, power means, a longitudinally movable and rotatable shaft having a gear secured to one end, a hand wheel secured to said shaft, said hand wheel being adapted to receive manual push-pull and rotational forces, said gear being selectively connectible through longitudinal movement of said shaft with any one of said two actuatable means, clutch means connecting said power means with said shaft for selective forward and

reverse drive, said shaft being selectively manually rotated through said hand wheel and power rotated through said power means in any longitudinal position thereof, a pair of dials supported on said shaft adjacent said hand wheel, and a single stationary pointer, one of said dials being calibrated to read traversing movement of said work table and the other to read vertical movement of said support, said dials being movable with the shaft and being adapted to selectively register with said pointer in accordance with the selected actuatable means, said dials being of annular form and being frictionally mounted on the shaft, said frictional engagement permitting annular movement of said dials for zeroing, and the like.

12. In a machine of the kind described including a transversely movable work table, a vertically movable work table support, and power means, in combination, mechanism for selectively connecting the power means with the work table for power traversing the same and with the work table support for power raising or lowering the same including a single movable power transmitting member alternately operatively connectible between the power means and the work table or work table support, and a single power reversing mechanism operatively connected to said member for reversing the power application for both traversing the work table and vertically moving the table support.

13. In a machine of the kind described including a transversely movable work table, a vertically movable work table support, and power means, in combination, mechanism for selectively connecting the power means with the work table for power traversing the same and with the work table support for power raising or lowering the same including a rotatable and axially movable member manually axially movable and selectively manually or power rotated, and a single power reversing mechanism operatively connected to said member for reversing the power application for both traversing the work table and vertically moving the table support.

14. In a machine of the kind described, in combination, a work table support, means mounting said work table support for vertical movement including means actuatable for imparting vertical movement to said support, a work table supported by said support for traversing movement, means actuatable for imparting trav-

ersing movement to said table, a rotatable and longitudinally reciprocable member, means connected to said member adapted for selective engagement with said support actuatable means and said table actuatable means, means for moving said member selectively longitudinally to engage said means connected thereto with said support actuatable means or said table actuatable means, means for rotating said member to effect movement of the selected actuatable means, and a single power reversing mechanism operatively connected to said member for reversing the power application for both traversing the work table and vertically moving the table support.

15. In a machine of the kind described including a transversely movable work table, a vertically movable work table support, and power means, in combination, mechanism for selectively connecting the power means with the work table for power traversing the same and with the work table support for power raising or lowering the same including a single movable power transmitting member alternately operatively connectible between the power means and the work table or work table support, manually operable means bodily movable for moving said power transmitting member into said selective connecting relation, said manually operable means being manually rotatable to adjust the selected connected work table or support independently of said power means, a pair of dials axially movable with said member, one dial being calibrated to read traversing movement of said work table and the other vertical movement of said support, and a single stationary pointer, said dials being movable into registry with said pointer to correspond to the power connection of the work table and support, respectively.
